HANDY TOP FOR CONTAINERS

Frederick C. Groman, Dodge City, Kans.

Application November 27, 1935, Serial No. 51,893

2 Claims. (Cl. 221—60)

This invention relates to closures for containers, and its general object is to provide a handy top for containers, in the form of a cap primarily designed for use with collapsible tubes, 5 that can be applied to the neck of tubes now in general use and retained thereon until the contents have been completely dispensed therefrom.

A further object of the invention is to provide a closure for a collapsible tube that allows the 10 contents to be easily and expeditiously dispensed therefrom when needed, but will seal the contents against foreign matter and air when not in use.

Another object of the invention is to provide 15 a dispensing cap for collapsible tubes that can be conveniently actuated with very little effort, is simple in construction, inexpensive to manufacture, easy to apply, and extremely efficient in operation, use and service.

20 This invention also consists in certain other features of construction and in the combination and arrangement of the several parts, to be hereinafter fully described, illustrated in the accompanying drawing and specifically pointed out in the appended claims.

25 In describing my invention in detail, reference will be had to the accompanying drawing wherein like characters denote like or corresponding parts throughout the several views, and in which:

30 Figure 1 is a front view illustrating my cap applied to a collapsible tube.

Figure 2 is a sectional view taken approximately on line 2—2 of Figure 4.

35 Figure 3 is a sectional view taken approximately on line 3—3 of Figure 1.

Figure 4 is a sectional view similar to Figure 3 with the parts in open or dispensing position.

40 Figure 5 is a sectional view of a slightly modified form.

45 Referring to the drawing in detail, it will be noted that I have illustrated my device as being applied to a collapsible tube, but I want it understood that it can be used with any type of container with which it is capable of performing its intended function.

The tube is indicated by the letter A and includes the usual threaded neck B to which my device is threaded securely in the same manner 50 as the cap now in general use, but of course my device is retained on the neck until the contents of the tube have been completely dispensed therefrom.

55 My device is in the form of a cap and includes a body 1 of cylindrical formation in that it in-

cludes a bore 2 extending longitudinally therethrough for a portion of its length and through the lower end thereof. The lower portion of the bore is threaded as at 3 to threadedly receive the neck B, as clearly shown in Figure 2. The bore 2 terminates adjacent the upper portion of the body and communicating with the upper end of the bore and extending laterally through the body is a passageway 4 which opens into an annular groove 5 extending about the body. 5

10 Mounted for rotation in the groove 5 is the valve means of my device which is preferably formed from a single strip of material arranged to provide a ring portion 6 received in the groove, with the end portions of the strip of material disposed in engagement with each other to provide fingers acting as a handle 7. The fingers are fixed together by a rivet or the like 8 which likewise holds the ring portion within the groove, as will be apparent. 15

10 In order to limit the rotation of the valve means on the body 1, I employ a stop means which includes a pin 9 extending through the ring portion and receivable within a recess 10 arranged in the groove as best shown in Figure 3. 20

The ring portion has arranged therein an opening 11 to register with the passageway 4, and an elongated outwardly flared recess 12 is provided in the outer surface of the ring portion about the opening 11, as best shown in Figure 1, 25 30 for the purpose of providing a pocket to receive a toothbrush or the like in removing a portion of the contents of the tube, as will be apparent.

In order to provide a leak proof connection between the ring portion and the body of my device, I employ a gasket 13 that is mounted in a recess 14 in the ring portion, and the gasket is disposed about the opening 11, but extends a considerable distance laterally thereof to overlie the outlet end of the passageway 4 to seal the same 40 when the valve means is in closed position, as shown in Figure 3. However, when the valve means is disposed to open position as shown in Figure 4, the opening of the gasket registers with the passageway 4 and the opening 11, to allow for 45 the passage of the contents of the tube therefrom.

45 In Figure 5 I have illustrated a slightly modified form, in that the gasket has been eliminated and the ring portion 6 is provided with a recess 15 to 50 receive the free portion of a pin 16 that is secured to the body 1, instead of to the ring portion, as shown in the preferred form.

55 In the use of my device with a collapsible tube, it will be obvious that the usual cap is removed

from the tube and the device is threaded thereon. When it is desired to dispense the contents of the tube therefrom, the handle 7 is moved to dispose the opening 11 in registration with the passage-way 4, as shown in Figure 4, and of course when the desired amount has been dispensed the valve is moved to its normal or closed position as shown in Figure 3.

It is thought from the foregoing description that 10 the advantages and novel features of my invention will be readily apparent.

I desire it to be understood that I may make changes in the construction and in the combination and arrangement of the several parts, provided that such changes fall within the scope of 15 the appended claims.

What I claim is:

1. A dispensing device for containers, comprising 20 a body having an annular groove therein, an outlet means opening into the groove, means for detachably connecting the body to a container with the outlet means in communication therewith, valve means formed from a single strip of material and including a ring portion mounted 25 for rotation in the groove, said ring portion having an opening therein to register with the outlet

means, sealing means for the outlet means and carried by the ring portion, means to limit the rotation of the ring portion and fingers formed on the ends of and extending outwardly from the ring portion, said fingers being fixed together in face 5 to face contact for securing the ring portion in the groove and for providing a handle for rotating the same.

2. A dispensing device for containers, comprising 10 the same and outlet means opening into the groove, means for detachably connecting the body to a container with the outlet means in communication therewith, valve means formed from a single strip of material and including a ring portion 15 mounted for rotation in the groove, said ring portion having an opening therein to register with the outlet means, and a recess in the outer surface thereof and being outwardly flared from the opening to provide an elongated pocket, fingers extending 20 from the ends of the ring portion, means for securing the fingers together to provide a handle for the valve means, and means to limit the movement of the valve means.

FREDERICK C. GROMAN.
